Primary Examiner — John R Yeh*(74) Attorney, Agent, or Firm* — Quickpatents, LLC; Kevin Prince(57) **CLAIM**

The ornamental design for a soap-dispensing sponge handle, as shown and described.

DESCRIPTION

FIG. 1 is a front perspective view of a soap-dispensing sponge handle, showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines depict portions of the soap-dispensing sponge handle that form no part of the claimed design.
